UNITED STATES PATENT OFFICE.

JOSEPH LEMMA, OF DETROIT, MICHIGAN, ASSIGNOR OF ONE-THIRD TO MARY LEMMA
AND ONE-THIRD TO BRUNO GARABELLI, BOTH OF DETROIT, MICHIGAN.

AUTOMATIC DOOR-OPERATING DEVICE.

Application filed January 31, 1927. Serial No. 164,794.

The object of my invention is to provide an automatic door operating device, adapted for installation with sliding doors and operating in a manner that will automatically 5 open or close the doors without aid of manual means.

Another object is to produce a door opening device that is adapted for installation with sliding doors and will operate automatically by pressure from the load of an 10 approaching vehicle.

A further object is to produce an automatic door opener, which operates solely by a system of levers and will operate to close 15 as well as to open the door.

A still further object is to provide an automatic door opening device that is simple in construction, easily and efficiently operated, and can be manufactured and installed at a 20 very low cost.

These several objects are attained in the preferred form by the construction and arrangement of parts more fully hereinafter set forth.

25 Similar parts on all drawings are marked by similar numerals.

Fig. 1, is the front view of the door with the operating mechanism attached thereto, showing the general arrangement of the 30 lever mechanism.

Fig. 2, is an end view of the door showing the relative position of the operating mechanism.

Fig. 3, is a sectional view taken on line 35 3-3 of Fig. 1, showing the operating levers and connections thereof to the door sections.

Fig. 4, is an alternate arrangement of the operating levers as may be applicable to door sections of large dimensions, as well as to 40 the ordinary type of door.

I will now describe more fully the detail construction of my device, referring to the drawings and the marks thereon.

45 My device is applicable to sliding doors only, such as are commonly employed in out-buildings, garages, warehouses, etc. The doors are ordinarily hung by door rollers, supported on suitable door tracks, attached to the building wall. My device is attached 50 to the exterior edge of each door and operated in a manner for opening each of the doors by a series of attached levers, which in turn are mounted on, and operated by a movable bridge beam positioned beneath the 55 center of the doors. The bridge beam car-

ries a side bridge section pivotally mounted on either side thereof, said bridge sections being also hinged at the outer edges thereof to fixed wall supports, and capable of receiving an approaching vehicle thereon, the bridge sections and attached beam settling in the bridge pit beneath the doors, drawing the lever mechanism therewith in a manner that will operate the levers for opening the 60 sliding doors.

65 The doors —1— are of ordinary type and design, of sliding doors commonly used for outside doors in garages, warehouses, etc., and are mounted upon a supporting track —2— which is fixedly attached to the wall —3— of the building. The doors —1— are provided with roller bearings —4— mounted on the top edge of each door panel, and extend over the track —2— in such a manner as to engage and rest thereon, the rollers —4— are free to operate and move the doors —1— along the track —2— in either direction, and in a manner incidental to the ordinary type of roller doors. Directly beneath the doors —1— and parallel therewith is mounted an operating bridge beam —5—.

70 The beam —5— is of a length equal to about twice the width of the double doors, and is supported at each end thereof by the rods —6—, which are suspended from the outer ends of the track —2— by eyebolts —7— fixedly attached to the track. At the lower end of the supporting rods —6— are mounted heavy coil springs —8—, connecting the ends of the rod with the bridge beam —5— and provide a spring support therefor. On each side of the bridge beam —5— is attached a movable bridge platform —9—, which are connected thereto, by the hinges —10— fixedly attached to the side walls of 75 the beam, and in a manner as to pivot the bridge platforms thereon. The bridge platforms —9— are of a length equal to the full width of the double doors, and of a sufficient width to allow the front wheels of an approaching vehicle to rest thereon, when the doors —1— are closed, both the bridge platforms —9— are also pivoted to the outer foundation walls —11— by the hinged bearings —12— fixedly attached to 80 the foundation, one bearing being placed at each of the outer corners of the bridge platform. The platforms and beam are held in a suspended position by the rods —6— and attached coil springs —8—, and as shown in 85

90 95 100 105 110

Fig. 1 of the drawings. Near each end of the beam —5— is mounted a pivot bearing —13— fixedly attached to the top wall of the beam. Pivotally attached to each of the bearings —13— outside the doors, is an operating bar —14— free to turn within the pivot support, in a plane parallel to the beam —5—, the operating bars —14— being of a length to extend slightly above the top edge of the door panels —1—, same being mounted on the bridge beam —5— at a distance from the door panels to allow each door to be opened the full required width before coming in contact therewith. At the top end of the operating bars —14— are the pivotally attached door arms —15— and the opposite end of arm —15— being attached to the top edge of the door panel —1— by the pin bolt —16— fixedly mounted within the door panel. Near the bottom of the operating bars —14— are also mounted door arms —17—, said arms —17— are also attached to the door panels —1— near the bottom thereof, by the pin bolts —18— also fixedly attached in the door panel —1—, the door arms —17— may be omitted if desired. Attached to the operating bars —14— are the operating arms —20—, the said arm —20— being pivoted thereto and having their outer ends pivotally attached to fixed wall blocks —21—, by means of the pin bolt —22— fixedly mounted within the wall blocks and projecting therefrom. The wall blocks —21— are fixedly attached to the wall —3— of the building and at a position outside of the supporting bars —6—. The system of arms in their pivoted position being connected directly with the bridge beam —5— and bridge platforms —9— are subject to any movement of the bridge platform when under load of an approaching vehicle, the said weight of the vehicle on the platform bridge —9— will lower the bridge beam into the bridge pit —23— directly beneath the platform and at the same time draw the operating bars —14— therewith. The connected operating arms —20— will turn about the fixed pivot pins —22— in the wall block, and move the fulcrum of the operating arms —14— outward away from door panels —1— and cause the top ends of both operating bars —14— to also move outward away from the doors, drawing the top of the door panel —1— therewith, by the connecting door arm —15—, also at the same time the connecting door arm —17— as pivotally attached to the bottom of the door panels —1— and to the operating bars —14—, is drawn backward by the swinging movement of all of the arms about the wall pivot —22— when the beam —5— is lowered, and draws the bottom of the door panels —1— therewith and opening both doors by direct action of the attached lever mechanism. When the load of the vehicle

is removed from either bridge platform —9—, the support springs —8— as attached to the ends of the bridge beam —5— will raise the bridge beam —5— to its original position and automatically close the doors, through the reverse movement of the operating levers. The length, position and ratio of the operating arms and fixed pivots, may be accurately determined for operating any desired size or type of door, within certain range limits. It is essential for efficient operation of the pivoted levers, that the two operating bars —14— are set at an angle leaning toward the top of the door panels —1—, and that both the operating arms —20— and door arms —17— be set at angles sloping downward toward operating bar connections, making them more effective in producing horizontal movement for opening the door panels, when drawn downward by the loaded bridge beam —5—.

An alternate form of operating arm is shown in Fig. 4, of the drawings, by providing a double extension arm —24— having one long arm —a— and one short arm —b— thereon. The double operating arm —24— is pivoted on the fixed wall pivot —22— the same as heretofore described, with the short arms —b— pivotally attached to the operating bar —14— and the long arm —a— connected to the lower edge of the door panel —1— by the door arm —25—, all operating in a manner as heretofore described. The length, position and ratio of the lever arms being all pre-determined to accomplish the uniform and consistent movement of the doors.

Having fully described my door operating device, what I claim and desire to secure by Letters Patent is:

1. An automatic door operating device to be used in combination with sliding door panels, for opening and closing same, comprising a horizontal bridge beam member placed beneath the sliding door panels and positioned at about the floor level, a bridge platform pivotally attached to the side of the bridge beam and extending therefrom in a position in front of the door panels, a spring support member attached to the bridge beam for holding same suspended in a horizontal position beneath the door panels, capable of settling when a super-load is resting on the bridge platform, a series of operating arms pivotally mounted on said bridge beam outside of the door panels and at a distance therefrom to allow the doors to open the required width without interfering with the operating levers, lever arms pivotally attached to the operating levers are connected directly to the door panels and an operating arm pivotally attached to said operating bars having the opposite end pivotally attached to a fixed wall block, all levers being so connected that the settling of the

bridge beam when loaded, will swing the connecting operating levers in a manner for sliding the doors open.

2. An automatic door operating mechanism to be used in combination with sliding door panels, for opening and closing same, comprising a horizontal bridge beam placed beneath the sliding door panels and positioned at about the floor level, said horizontal bridge beam being suspended by spring supports, bridge platforms pivotally attached to the side of said bridge beam and extending therefrom in a position in front of the doors and so arranged as to settle 15 when a super-load is placed thereon, an operating bar pivotally mounted on each end of the bridge beam outside of the sliding door panels and in a plane therewith, door arms pivotally attached to said operating 20 bars and pivotally attached to the sliding door panels, an operating arm pivotally attached to the operating bars also having one end of said operating arm pivotally attached to a fixed wall block, all of said operating 25 arm members so positioned and proportioned as to cause the doors to open upon the settling of the bridge beam and to cause the doors to close upon the raising of the bridge beam.
- 30 3. An automatic door operating mechanism to be used in combination with sliding door panels for opening and closing same, comprising a horizontal bridge beam placed beneath the door panels and parallel therewith, said bridge beam being of a length 35 equal to about twice the width of the sliding door panels and positioned at about the floor level, said bridge beam being suspended by spring supports in a manner to allow the 40 bridge beam to settle thereon when under load, bridge platforms pivotally attached to the side of said bridge beam in front of the door panels and so mounted as to cause the settling of the bridge beam when the super- 45 load is placed thereon, an operating bar pivotally mounted on the top of the bridge beam near each end thereof, and in a plane with the door panel, said operating bars extend-

ing to near the top of the door panels and inclined in an angular position toward the top of the door panels, said operating bars being connected to the door panels by door arms pivotally attached to both operating arms and door, an operating arm pivotally attached to each operating bar and having its opposite end pivotally attached to a fixed wall block outside the door and positioned at such an angle that the settling of the bridge beam, when loaded will pivot and turn the operating bars attached thereto in a direction for opening the attached door panels and will close the door panels by the raising of the bridge beam when the load is removed therefrom.

4. An automatic door operating device to be used in combination with sliding door panels, for opening and closing same, comprising a horizontal bridge beam placed below the door panels, said beam being of a length of about twice the width of the door panels and suspended by spring supports mounted thereon, a bridge platform pivotally attached to the side of the bridge beam and so mounted as to cause the bridge beam to settle when a super-load is placed thereon, an operating bar pivotally mounted at each end of the bridge beam near the end thereof, said operating arm being positioned in a plane with the door panels extending to near the top thereof and inclined at an angle toward the top of the door, an operating arm attached to said operating bar and having the opposite end thereof pivotally mounted to a fixed wall block positioned outside of said operating arm and so positioned that the settling of the attached door beam will cause an outward movement of the operating bars therewith and a door arm pivotally attached to the said operating bar connected in a manner that will cause the sliding door panels to open and close as the bridge beam is lowered or raised upon its suspended spring supports.

In witness whereof, I sign these specifications.

JOSEPH LEMMA.
